J. O. Helgeson.

Dear Swift Attorney

UNITED STATES PATENT OFFICE.

JOHAN O. HELGESON, OF SOLDIERS GROVE, WISCONSIN.

DRAFT-EQUALIZER.

No. 889,006.

Specification of Letters Patent.

Patented May 26, 1908.

Application filed April 10, 1907. Serial No. 367,375.

To all whom it may concern:

Be it known that I, JOHAN O. HELGESON, a citizen of the United States, residing at Soldiers Grove, in the county of Crawford 5 and State of Wisconsin, have invented a new and useful Draft-Equalizer; and I do hereby declare the following to be a full, clear, and exact description of the invention, such as will enable others skilled in the art to which 10 it appertains to make and use the same.

This invention relates to a draft equalizer and the object thereof is to provide a device of this design adapted for from four to eight or ten or more horses; the different parts of 15 the equalizer being so arranged as to successfully equalize the draft on each and every horse, and designed so as to bunch the horses close together.

The equalizer comprises a plurality of 20 doubletrees and swingletrees connected together by clevises and chains, as clearly shown in the drawings. These chains may be or may not be so arranged as to coöperate with pulleys, in lieu of fixed connections.

25 This invention comprises further objects and combinations of elements which will be hereinafter more fully described, shown in the accompanying drawings, and the novel features thereof will be pointed out by the 30 appended claims.

To obtain a full and correct understanding of the details of construction, combinations of features, elements and advantages, reference is to be had to the hereinafter set forth 35 description and the accompanying drawings in connection therewith, wherein

Figure 1 is a plan view of the equalizer, illustrating the same adapted for use in connection with ten horses. Fig. 2 is a view of 40 a modified form illustrating the invention adapted for use in connection with eight horses.

Making renewed reference to the accompanying drawings, wherein similar reference 45 characters indicate corresponding parts in the several illustrations, by figures, 1 designates an equalizer beam, that is the main beam which is designed for connection to the object to be drawn. To this beam 1 is connected a pair of supplemental equalizing beams 2 by means of clevises or chains 3, as clearly shown; to the outer ends of the beams 2 is connected a second pair of supplemental 50 equalizing beams 4 by means of clevises or chains 5. Each supplemental beam 4 is

provided with a pair of swingletrees 6 and 7, as clearly shown in Fig. 1.

Connected to the ends 8 of the beams 2, as at 9, is the chain 10 which is adapted to coöperate with a ring 11, to which a second main equalizing beam 12 is connected, by means of a clevis or chain 13. Carried by outer ends of the beam 12 are clevises or chains 14 which connect with a pair of supplemental equalizing beams 15 to the outer 60 ends of which the clevises or chains 16 are connected, which connect with a pair of second supplemental equalizing beams 17, as clearly shown.

The supplemental beams 15, are provided 70 with slots 15^a in which sliding members 15^b are mounted, as clearly shown in the drawings. Said beams 15, are provided with additional slots 15^c disposed upon a plane at right angles to the slots 15^a, and positioned 75 in the slots 15^c, are the staples 15^d which are carried by said sliding members; these staples are for the purpose of changing the position of the chains 14, which are connected to the main equalizing beam as clearly shown. 80 The said beams 15 are provided with screw-threaded elements 15^b, designed for the purpose of holding the members 15^b in adjusted position. This construction is for the purpose of regulating and equally distributing 85 the draft throughout the plurality of equalizers, as will be clearly manifest.

To equalize the draft, caused by the pull upon the beams 15 and 17, the inner ends of the beams 15 are provided with a chain connection 18, which is provided with a ring 19 to which a clevis or chain 20 is connected, which has pivotal connection with an equalizing beam 21 which in turn is provided with a pair of swingletrees 22, as clearly shown. 95

The pull, when this device is in practical use, upon the outer ends of the beams 2 is equalized by the pull upon the beam 12 which is connected by the chain 10 to the beams 2.

The beams 17 are each provided with a pair 100 of swingletrees 23, the connection between which and the said beams 17 being obtained by the clevises or chains 24 and 25, as clearly shown in the drawings.

Fig. 2 illustrates a modification of the invention, in which an additional set of equalizers are shown, and the swingletrees 6, 7 and 23 are eliminated.

It is to be understood that various changes and modifications may be employed in the 110

construction and embodiment thereof, combinations of features, and elements, without in any way departing from the spirit and scope of the invention covered by the claims 5 thereof; it being understood that whatever variations or modifications are employed must fall within the scope of the appended claims.

From the foregoing, the essential features, 10 elements and the operation of the device, together with the simplicity thereof, will be clearly apparent, and, when manufactured in accordance with the invention, an inexpensive market will be easily obtained there- 15 for.

Having thus fully described the invention, what is claimed as new and useful by the protection of Letters Patent, is:—

In a draft equalizer, the combination of a 20 plurality of equalizers connected in multiple, so as to equalize the draft on eight or ten

horses, chains for connecting the equalizers in multiple, said equalizers comprising main and supplemental equalizing beams, one pair of the supplemental equalizing beams 25 having slots, sliding adjustable members positioned therein, said members having chain connection with one of the main equalizing beams, said supplemental equalizing beams having screw-threaded members to hold the 30 sliding members in adjusted position and doubletrees having swingletrees connected thereto carried by the said supplemental beams.

In testimony whereof I have signed my 35 name to this specification in the presence of two subscribing witnesses.

JOHAN O. HELGESON.
